UNITED STATES PATENT OFFICE

167,928

MAILBOX

Samuel H. Coward, Jr., Jacksonville, Fla., assignor
to Liberty Glass Company, Sapulpa, Okla.

Application September 13, 1950, Serial No. 12,165

Term of patent 3½ years

(Cl. D74—9)

To all whom it may concern:

Be it known that I, Samuel H. Coward, Jr., a citizen of the United States of America, residing at Jacksonville, in the county of Duval and State of Florida, have invented a new, original, and ornamental Design for a Mail Box, of which the following is a specification, reference being had to the accompanying drawing, forming part thereof.

Figure 1 is a perspective view of a mail box, showing my new design.

Figure 2 is a transverse sectional view.

Figure 3 is a rear elevational view.

My design for a mail box is characterized by a rectangular back piece integrally formed along its top edge with a transversely curved and upwardly and forwardly extending flange. A half cylindrical, transparent front member is hinged to the back piece adjacent the lower edge thereof and is provided intermediate its ends with a latch member in the form of a metal strap

curved to correspond to the curvature of said front member and carrying at its upper end a reverse upward curve that corresponds to the curvature and overlies a portion of the upper extension of the back piece.

I claim:

The ornamental design for a mail box, as shown and described.

SAMUEL H. COWARD, JR.
